W. S. PACA

CALL DISTRIBUTING SYSTEM

Filed Sept. 4, 1919

Patented May 1, 1923.

1,453,321

UNITED STATES PATENT OFFICE.

WILLIAM S. PACA, OF OIL CITY, PENNSYLVANIA, ASSIGNOR TO THE STROMBERG-CARLSON TELEPHONE MANUFACTURING COMPANY, OF ROCHESTER, NEW YORK, A CORPORATION OF NEW YORK.

CALL-DISTRIBUTUTING SYSTEM.

Application filed September 4, 1919. Serial No. 321,675.

To all whom it may concern:

Be it known that I, WILLIAM S. PACA, a citizen of the United States, residing at Oil City, in the county of Venango and State of Pennsylvania, have invented certain new and useful Improvements in Call-Distributing Systems, of which the following is a full, clear, concise, and exact description.

This invention relates to telephone systems, and more particularly to such systems in which line circuits terminating at a central office are provided with multiple jacks, and associated line signaling devices before the different operators' positions.

15 In the equipment of such systems it is customary to divide the switchboards into sections, at each of which a multiple jack and associated signal lamp are provided for each telephone line. In such switchboards the lamps individual to each calling line operate simultaneously on the initiation of a call and it frequently happens that several operators attempt to answer the same call with the result that there is confusion 20 and loss of time.

In applicant's Patent 1,353,065, granted September 14, 1920, it was proposed to eliminate the difficulty above mentioned by terminating the lines in a so-called "main" 30 section of the switchboard and also at sections on an "auxiliary" board. In that application it was proposed that the initiation of a call would light only the signal lamp at the main board unless several calls were 35 awaiting the attention of that operator, in which case the line signals of waiting lines would be lighted at the several sections of the "auxiliary" board.

40 In accordance with the present invention it is proposed to arrange a telephone system having main and auxiliary sections so that the several sections can co-operate in various ways depending on the condition of traffic.

According to one arrangement means are 45 operated so that when a predetermined number of calls are waiting at the main positions, the line signals at the auxiliary positions will burn in a distinctive manner, such as steadily, and when a greater number of 50 predetermined calls are waiting the attention of the main operator, the line signals of these lines at the auxiliary positions will be operated in a different manner, such as by 55

The present system is also arranged so that all the line signals appearing on the main board may also burn on the auxiliary board irrespective of the number of calls to be completed, and means, such as an interrupter, may be operated to flash the line signals of the calling lines on the "auxiliary" board when a predetermined number of calls are awaiting completion.

This system is further arranged so that all line signals on calling lines may be lighted on the auxiliary board, and no line signals lighted on the main board, in which case the auxiliary line lamps burn steadily.

It is the object of the present invention to provide simple means for changing from each of these various methods of operation to the other.

The drawing diagrammatically represents a portion of a telephone system showing some of the circuits associated with two subscribers' lines and indicating that these lines terminate in multiple jacks located at "main" and "auxiliary" sections of the switchboard. Each multiple jack has associated with it the well known lamp signal.

In the system of the present invention several methods of operation are provided for, depending on the adjustment of the key K. With the key K in its normal or vertical position, when a subscriber as at L' initiates a call by removing his receiver from its switchhook, the line relay 2 individual to his line is actuated to operate the line signal also individual to his line in a circuit extending from ground, inner armature and front contact of line relay 2, lamp 3, conductor 4, spring 5 and its normal contact, winding of the marginal relay 6, winding of pilot relay 7, to grounded battery. The pilot relay 7 is actuated in this circuit and lights the pilot lamp to indicate that one or more calls are awaiting extension at the operator's position. If now a call is initiated on a second line extending to the same main position, such as 12, then its line relay 8 will be operated to close a circuit for its associated lamp signal 9 in multiple with the circuit of the line signal 3. The marginal relay 6 is so adjusted that it will operate only when two or more calls are extended to the same position or main board at the same time. Since under the present assumption there are two calls simultaneously

awaiting the attention of the operator at the main board here disclosed, the marginal relay 6 attracts its armatures to close a circuit from grounded battery, winding of the marginal relay 10, conductor 11, spring 12 and its normal contact, conductor 13, armature and front contact of relay 6, spring 14 and its normal contact, conductor 15, through the lamps 16 associated with the multiple jacks of the calling lines at the auxiliary boards to ground at the outer front contacts and armatures of line relays 2 and 8. The marginal relay 10 is so adjusted that it operates only when the sets of lamps individual to three different calling lines are lighted and when it attracts its armature it closes a break point in a shunt path extending to the interrupter 11 to intermittently operate the lamps 16 of calling lines at the auxiliary positions. It will thus be seen that with the key K in its normal position when one call is extended to the main board, the lamps associated with the multiple jacks of the calling line at the auxiliary positions will not be lighted. When, however, two simultaneous calls are extended to the operator's position at the main board, the lamps associated with the multiple jacks of the calling lines at the auxiliary boards will burn steadily, and when three or more calls are extended to the operator's position at the main board, the lamps associated with the multiple jacks of the calling lines at the auxiliary positions will be caused to flash.

When the key K is adjusted to the left, the initiation of a call will cause the lighting of the lamps individual to this line on the main board and also at the auxiliary positions, and when three or more calls are awaiting extension the lamps on the auxiliary board are caused to flash. This will be understood by tracing the following circuits. Under the present assumption when either the line relay 2 or 8 is actuated, its associated lamp is lighted over conductor 4, normal contact and the spring 5 of the key, and windings of relays 6 and 7 to grounded battery. The lamps on the auxiliary board associated with the calling line are also operated through a circuit traceable from ground at the armature of the actuated line relay, through the lamps 16, conductor 15, spring 14 and its alternate contact, spring 12 and its contact, conductor 11, winding of relay 10 to grounded battery. In this case as in that previously described, the relay 10 is operated when three or more simultaneous calls are awaiting extension, and the interrupter 17 intermittently shunts the lamps 16 causing them to flash.

When the key K is adjusted to the right, all line signals of calling lines will be lighted at various positions of the auxiliary board, while no line signals will be lighted

on the main board. The interrupter 17 is also inoperative at this time so that the line lamps at the several positions of the auxiliary board will burn steadily when calls are originated irrespective of the number of calls awaiting extension. Let it be assumed that the line L' originates a call while key K is thrown to the right. The operating circuit of the lamp 3 individual to the line L' is now open at the spring 5 and its normal contact at the key, so that this lamp will not be lighted. The lamps 16 individual to the line L' are, however, operated in a circuit closed from ground, outer armature and front contact of relay 2, lamps 16, conductor 15, spring 5 and its alternate contact, and winding of marginal relay 6 and relay 7 to grounded battery. The circuit of the marginal relay 10 is open at spring 12 and its contact so that the interrupter 17 is not effective at this time.

It will be understood that one or more operators' positions may be provided at each of the boards designated "main" and "auxiliary" boards without departing from the spirit of the present invention.

What I claim is:

1. The method of handling telephone calls in a system having primary and secondary operators which consists in signaling only the primary operators when less than a predetermined number of calls are awaiting attention, but in signaling said secondary operators when a predetermined number of calls are awaiting said primary operators, and in signaling said secondary operators in a distinctive manner when a number of calls greater than the predetermined number are awaiting attention of the primary operators.

2. The method of handling telephone calls in a system having primary and secondary operators which consists in signaling only the primary operators when less than a predetermined number of calls are awaiting attention, but in signaling said secondary operators when a predetermined number of calls are awaiting said primary operators, in signaling said secondary operators in a distinctive manner when a number of calls greater than the predetermined number are awaiting attention of the primary operators under one condition of traffic, and under another condition of traffic in signaling both primary and secondary operators on all calls, and in operating all of said signals in a distinctive manner when a predetermined number of calls are awaiting attention of said operators.

3. The method of handling telephone calls in a system having primary and secondary operators which consists in signaling only the primary operators when less than a predetermined number of calls are awaiting attention, but in signaling said secondary op-

- erators when a predetermined number of calls are awaiting said primary operators, and in signaling said secondary operators in a distinctive manner when a number of calls 5 greater than the predetermined number are awaiting the attention of the primary operators under one condition of traffic, and under another condition of traffic no signals will be given to the primary operators on 10 any call, and the secondary operators will always be signaled in the same manner irrespective of the number of calls awaiting attention.
4. The method of handling telephone calls 15 in a system having primary and secondary operators which consists in signaling both primary and secondary operators and in signaling said operators in a distinctive manner when a predetermined number of calls 20 are awaiting attention under one condition of traffic and under another condition of traffic in signaling only said secondary operators.
5. In a telephone system, a plurality of 25 signal lamps, a current measuring device in series with certain of said lamps, and a second current measuring device co-operating with the first to light and flash certain of said lamps.
6. In a telephone system, primary and secondary signals, circuits for each of said groups of signals, a marginal relay in series with the primary signals, a second marginal relay arranged to be connected in series with said secondary signals, and means 35 jointly controlled by said relays to distinctively actuate said signals. 30
7. In a telephone system, primary and secondary lamps, circuits for each of said groups of lamps, a marginal relay in series 40 with the primary lamps, a second marginal relay arranged to be connected in series with said secondary lamps, and means jointly controlled by said relays to distinctively actuate said lamps. 45
8. In a telephone system, primary and secondary lamps, circuits for each of said lamps, a marginal relay controlled over the circuit of the primary lamps, a second marginal relay arranged to be controlled over a 50 circuit of said secondary lamps, and a shunting circuit completed at said marginal relays to distinctively actuate said secondary lamps. 50

In witness whereof, I hereunto subscribe 55 my name this 21st day of August, A. D. 1919.

WILLIAM S. PACA.
